Yay Mats Stylish Extra Large Baby Play Mat. Sold on Amazon.com. Jan. 24, 2018. Accessed on Mar. 12, 2020. (Year: 2018).*

Primary Examiner — Kevin K. Rudzinski*Assistant Examiner* — Clare Ann Gannon(74) Attorney, Agent, or Firm — Collard & Roe P.C.

(57)

CLAIM

The ornamental design for a play mat, as shown and described.

DESCRIPTION

The sole FIGURE is a top plan view of a play mat, showing my new design. The play mat is planar, and the side and bottom views form no part of the claimed design.

1 Claim, 1 Drawing Sheet(56)
